Application October 2, 1953, Serial No. 27,060

Term of patent 14 years

(Cl. D47—7)

To all whom it may concern:

Be it known that I, Manuel M. Lihn, have invented a new, original, and ornamental Design for a Stocking or Similar Article, of which the following is a specification, reference being had to the accompanying drawing, forming a part hereof.

The figure is a rear elevational view of a stocking showing my new design. The front elevation is conventional in appearance.

The characteristic feature of my design resides in the combination on a lady's full fashioned stocking of the converging wales at the rear seam, both in the flare narrowings above the knee and in the leg narrowings at the calf and ankle portions, without visible fashioning marks or narrowing points, as shown.

I claim:

The ornamental design for a stocking or similar article, as shown and described.
